UNITED STATES PATENT OFFICE

2,344,273

DISPLAY STAND

Herbert A. Simon, Brooklyn, N. Y.

Application October 5, 1943, Serial No. 505,011

3 Claims. (Cl. 211—72)

This invention relates to improvements in display devices and more particularly to a folding cardboard display stand.

One of the important features of the invention is to provide a display device embodying a main display panel having a folding tray structure connected thereto which enables the flat folding of the device for compact packing and shipping, and which tray structure may be unfolded and interlocked with the display panel to hold the tray structure in set up position forward of the display panel.

Another feature of the invention resides in a folding display device in which a multi-compartment tray extends forward of a main display panel when the device is set up for use, the height of the tray being considerably less than the height of the display panel to expose advertising matter adapted to be arranged on the front thereof.

A further feature of the invention is the provision of a standing display device embodying a multi-compartment tray in which articles of merchandise may be segregated in an orderly manner for display and sales purposes.

Other novel features of construction will appear as the following specification is read in conjunction with the accompanying drawing, in which:

Figure 1 is a perspective view of the folding display device in set up position for use.

Figure 2 is a top plan view.

Figure 3 is an enlarged vertical sectional view on the line 3—3 of Figure 1.

Figure 4 is a perspective view of the display devices in flat collapsed position.

Referring to the drawing by reference characters, the numeral 10 designates a folding display stand in its entirety and which is constructed in accordance with the invention now to be specifically described.

The display device 10 includes a single blank of cardboard A which is substantially rectangular in shape. The blank A is hinge scored at 11 inwardly from its lower end and transversely thereof to divide the blank into a main display panel 12 and a folding bottom wall 13. Carried by the free forward edge of the bottom wall 13 is a front and end wall forming section formed from a single elongated blank of cardboard B. The front wall is designated 14 to which the end walls 15—15 are integrally connected along parallel hinge scores 16—16. Integral with the bottom of the front wall 14 and extending the length thereof is an attaching glue flap 17, the same being connected to the front wall along a hinge

score 18. The glue flap 17 is adhesively secured to the bottom wall 13 adjacent its free front edge. The front wall 14 and end walls 15—15 are relatively narrow compared to the height of the display panel 12 so that the tray formed by these walls is considerably shallow compared to the height of the panel 12 to expose the front of the panel on which advertising matter is adapted to be printed. Also, the length of the front wall 14 is less than the width of the panel 12 to facilitate the interlocking of the end walls 15—15 with the panel 12 in a manner presently to be explained. Extending from and integral with the free side edges of the end walls midway thereof, 15 are locking tongues 19—19, the corners of which are rounded. The panel 12 is provided with slots 20—20 which are substantially in alignment with the hinge scores 16—16 to respectively interfittingly receive the tongues 19—19 when the tray forming walls are folded into set up position.

Carried by the inner side of the front wall 14 is an elongated partition forming strip of cardboard C, the same being transversely hinge scored on the spaced parallel lines 21—21 to divide the same into an attaching panel 22 and partition wall flaps 23—23. Integral with the free side edge of each partition wall flap 23 midway of the height thereof is a locking tongue 24, the corners of which are rounded. The attaching panel 22 is adhesively secured to the inner side of the front wall 14 centrally thereof. In substantial alignment with the hinge scores 21—21 are slots 25—25 in the display panel 12, which with the slots 20—20 form a transverse row of slots across the panel 12. The attaching panel 22 is of a height equal to or less than that of the front wall 14. The partition flaps 23—23 are of a shape and height corresponding to that of the end walls 15—15.

In practice, assume that the display stand 10 is in flat unfolded position as shown in Figure 4. To set up the display device, the operator manually swings the display panel 12 on the hinge score 11 to a vertical position at right angle to the bottom wall 13. The partition flaps 23—23 are now swung on the hinge scores 21—21 to a position at right angles to the front wall 14, and likewise, the end walls 15—15 are swung on the hinge scores 16—16 to substantially parallel the partition wall flaps. Next, the front wall 14 is swung upward on the hinge score 18 and just prior to the limit of this swinging movement, the tongues 19—19, 24—24 are inserted into the respective slots 20—20 and 25—25. The slots are of sufficient length to receive the

tongues during this swinging movement but are of a width to enable a tight friction fit between the side walls of the slots and the opposed flat sides of the respective tongues, whereby to securely hold the folded parts in their folded position. With the walls and partitions thus folded a multi-compartment tray is provided forward of the main display panel 12. Three separate compartments D are formed, but more or less may be provided, depending upon the number of partition walls 23. Merchandise to be displayed and sold may be orderly placed in the compartments D.

To aid in rigidly supporting the display device in an upstanding set up position, a conventional folding cardboard easel 26 is centrally attached to the rear of the main display panel 12.

Whereas the display device 10 is shown in flat collapsed position in Figure 4, the length of the same may be shortened by folding the bottom wall 13 over the display panel 12, whereupon the front wall 14, end walls 15, and partition walls 23, all overlie the panel 12.

While I have shown and described what I consider to be the preferred embodiment of my invention, I wish it to be understood that such changes in design and construction as come within the scope of the appended claims may be resorted to if desired without departing from the spirit of the invention.

Having thus described the invention, what I claim as new and desire to secure by Letters Patent of the United States, is:

1. A folding cardboard display stand comprising a display panel, a bottom wall integral with the bottom of the display panel and hingedly connected thereto along a hinge score, a front wall hingedly connected to the front of the bottom wall, end walls integral with the ends of

the front wall and connected thereto along hinge scores, and locking tongues integral with the free side edges of the end walls and extending therefrom, said display panel having slots therein for interfittingly receiving the respective tongues, said bottom, front, end walls, and panel cooperating to provide a forwardly extending tray relative to said display panel.

10 2. A folding cardboard display stand as set forth in claim 1 in which the height of the front and end walls is considerably less than that of the display panel to expose a substantial portion of the same to view.

15 3. A folding cardboard display stand comprising a display panel, a bottom wall integral with the bottom of the display panel and hingedly connected thereto along a hinge score, a front wall hingedly connected to the front of the bottom wall, end walls integral with the ends of the front wall and connected thereto along hinge scores, and locking tongues integral with the free side edges of the end walls and extending therefrom, said display panel having slots therein for interfittingly receiving the respective tongues, said bottom, front, end walls, and panel cooperating to provide a forwardly extending tray relative to said display panel, spaced transverse partition walls hinged to the inner side of the front wall, locking tongues integral with the free sides of the partition walls, said display panel having complementary slots for respectively receiving the tongues of the partition walls, said bottom wall, front wall, end walls, and partition walls being of considerably less height than the display panel to expose a substantial portion of the front of the display panel to view.

30 35 HERBERT A. SIMON.
